CLAIM

The ornamental design for a pruner, as shown and described.

DESCRIPTION

FIG. 1 is a front perspective view of a pruner showing our new design;

FIG. 2 is a front elevational view thereof;

FIG. 3 is rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The phantom lines depicted in the accompanying figures are intended for purposes of illustration only and are not a part of the design.

The broken line showing of pruner elements is for illustrative purposes only and forms no part of the claimed design.
